UNITED STATES PATENT OFFICE.

ANDREW TAGGART, JR., OF ALLEGHENY, PENNSYLVANIA.

BOILER-FLUE.

SPECIFICATION forming part of Letters Patent No. 759,043, dated May 3, 1904.

Application filed August 26, 1903. Serial No. 170,870. (No model.)

To all whom it may concern:

Be it known that I, ANDREW TAGGART, Jr., a citizen of the United States of America, residing at Allegheny, in the county of Allegheny and State of Pennsylvania, have invented certain new and useful Improvements in Boiler-Flues, of which the following is a specification, reference being had therein to the accompanying drawings.

10 This invention relates to certain new and useful improvements in boiler-flues, and has for its object to provide a simple but efficient connection between the ends of the boiler-flues and the flue-sheets, whereby the flues shall be absolutely prevented from leaking at their point of connection with the flue-sheets and at the same time allow the water to reach all the exposed portions of the boiler and the flues thereof.

20 A further object of my invention is to construct a flue of this character which may be advantageously employed in connection with different forms of boilers—such as locomotive-boilers, stationary boilers, marine boilers, or 25 the like—and a still further object is to so connect the flues to the flue-sheets as to materially increase the life of the flue.

30 A still further object of the present invention is to connect the flues to the flue-sheets in such a manner as to provide an even interior diameter throughout the length of the flue, permitting of the latter being more readily cleaned than in cases where the flues are connected to the flue-sheets by devices inserted 35 in the interior of the flues, at the ends thereof.

35 A further object of the invention is to construct a flue which will not become loosened by the exhaust, as is usually the case in the flues now ordinarily employed.

40 Further objects are sought to be obtained in the present invention, and these, together with those above noted, will be hereinafter more fully described and specifically pointed out.

45 In describing the invention in detail reference is had to the accompanying drawings, forming a part of this specification, and wherein like numerals of reference indicate like parts throughout the several views, in which—

50 Figure 1 is a longitudinal sectional view of

a part of a boiler-flue and a flue-sheet, showing the application of a ferrule for securing the flue in position. Fig. 2 is a like view showing the flue secured in position without the ferrule, employing only an inner ring. 55 Fig. 3 is a like view showing the employment of a combustion-ring in the end of the flue.

In the accompanying drawings, 1 indicates a flue formed of a hollow cylindrical tube of the ordinary construction used in steam-boilers. In the different views I have shown different manners of securely fastening the end of this flue in the flue-sheet 2, the principle involved in each of the methods being the same. In each construction the end of the 60

flue 1 is flanged and this flange 3 turned in against the flue - sheet 2, where it may be brazed, as at 4 in Fig. 3, and in the construction shown in Figs. 1 and 2 the flange may, if desired, be also brazed to the flue-sheet 2. 65

In the construction shown in Fig. 1 the end of the flue is inserted in a ferrule 5, the latter being placed in the opening in the flue-sheet 2, and after being placed in position this ferrule is expanded by means of an expander or 70

other suitable tool, so as to thread the same into the threads 6 in the walls of the opening in the flue-sheet. The inner ring 7 is placed over the inner end of the ferrule 5 and is preferably brazed both to the ferrule and to the 75

inner face of the flue-sheet 2. In Fig. 2 I show the inner ring 7' of angular shape in cross-section, and in this view I show this ring as brazed both to the flue 1 and to the inner face of the flue-sheet 2. When using 80

this form of ring, I may dispense with the ferrule 5 and insert an expander into the end of the flue, whereby to expand the latter into threaded engagement with the threads in the flue-sheet 2. In Fig. 3 I also show a flue expanded into threaded engagement with the opening in the flue-sheet 2, and in this construction I may also braze the ring 7' to the flue-sheet and to the flue. In practice the ferrule and also the inner ring are preferably 85

constructed of copper, as this material has been found to give the best results. If desired, the flue-sheet may be interiorly screw-threaded and the ferrule formed with exterior screw-threads for securing the ferrule to 90

95

the flue-sheet; but generally in practice the threads in the walls of the opening in the flue-sheet are merely circular grooves, and the ferrule is expanded, so as to force a part of the outer surface of said ferrule into said grooves, whereby to hold the ferrule securely in position. This is also true of the construction in which the flues are secured direct in the flue-sheet. In Fig. 3 I have also shown 10 the use of a combustion-ring 8, which is of an original diameter to permit of its being brazed within the flue, as shown. The use of this ring has been found to increase the combustion within the flue by reason of the ingress and 15 egress of the flue being lessened, and consequently the provision within the flue of greater space or area for expansion. The employment of this ring also serves to protect the flue materially, as it prevents cinder friction at the 20 ends of the flue, as the cinders striking against this ring instead of coming in direct contact with the flue ends are caused to be projected into the flue for a greater distance before striking the flue, or, as it were, being caused 25 to practically "float" through the flue. The employment of this flue-ring therefore dispenses with the use of what are commonly known as "safe ends."

It is to be observed that with the construction 30 of boiler-flue herein described for either of the different forms the expansion of the flues and the flue-sheet are equal, owing to the brazing of the flues to the flue-sheet. It is also to be noted that every flue acts as a 35 stay-bolt for the boiler, being brazed into the flue-sheet, and consequently held intact at all

times therewith, making the boiler an absolutely safety-boiler.

While I have herein shown and described the invention in detail as it has been practiced by me, yet it will be evident that in the practice of the invention various changes may be made in the details of construction without departing from the general spirit of my invention.

Having fully described my invention, what I claim as new, and desire to secure by Letters Patent, is—

1. A boiler-flue comprising a hollow cylindrical tube passed through the flue-sheet and having its extending end flanged outwardly 50 and engaged against the flue-sheet, a ferrule in the flue-sheet and through which the flue extends with the said ferrule brazed onto the flue, and an inner ring brazed against the inner face of the flue-sheet and surrounding the 55 flue and ferrule, substantially as described.

2. A boiler-flue comprising a tube having its end flanged outwardly to bear against the flue-sheet, and a ring brazed to the opposite side of said sheet and surrounding said tube. 60

3. A boiler-flue comprising a tube having its end flanged outwardly to bear against the flue-sheet, a ferrule surrounding said tube, and a ring brazed to the opposite side of said sheet and to said ferrule. 65

In testimony whereof I affix my signature in the presence of two witnesses.

ANDREW TAGGART, Jr.
